PHONOGRAPH PICK-UP ARM

Walter O. Stanton, Laurel Hollow, N. Y.

Application October 17, 1957, Serial No. 48,138

Term of patent 14 years

(Cl. D26—14)

FIG. 1

FIG. 2

FIG. 3

Fig. 1 is a perspective view of a phonograph pick-up arm, showing my new design;

Fig. 2 is a bottom plan view; and

Fig. 3 is a side elevational view, the opposite side thereof being substantially a mirror image thereof.

The dominant features of my new design are shown in solid lines in the drawing.

I claim:

The ornamental design for a phonograph pick-up arm, as shown and described.
